MACHINE FOR REINFORCING CLOTHESPINS

John R. Nolan, Larchmont, N. Y.

Application October 1, 1942, Serial No. 460,406

16 Claims. (Cl. 1—2)

This invention relates to means for applying to and confining within a bifurcated wooden clothespin a reinforcing element which is effective to prevent the splitting of the body of the pin when the prongs thereof are subjected to excessive spreading strain while the clothespin is in service.

In accordance with the principle of my invention metallic reinforcing elements having spaced legs are efficiently positioned at and driven into the crotch portions and lengthwise of the interior of the bodies of succeeding clothespins in such manner that the legs of each element diverge laterally from the respective angular corners of the clothespin.

In carrying out the invention in the preferred way a metallic reinforcing element of substantially U-form is embedded in the body at the crotch of the clothespin, the legs of the element being forced through the angular corners of the crotch and coincidentally spread laterally, whereby the extremities of the diverging legs when the element is driven home in the direction of the head of the clothespin, extend lengthwise into the body of the pin to points a greater distance apart than the width of the crotch, and whereby the connective portion of the legs extends transversely of the crotch. Thus the diverging legs, which are firmly embedded in the solid body of the clothespin, diagonally intersect the lines of the grain passing through the respective corners of the crotch, and in consequence such legs co-act with their short connective portion to prevent the splitting of the body of the clothespin should the prongs be subjected to excessive spreading strain while in service.

The reinforcing element is introduced in the flaring mouth of the space between the prongs of the clothespin and thence the element, legs leading, is forcibly driven toward the crotch of the clothespin, the points of the legs being guided and supported by the inner parallel walls of the respective prongs. As the points approach the crotch of the clothespin they are forcibly deflected laterally into and through the respective opposed corners of the crotch, thus penetrating lengthwise the solid body of the pin a determined distance. This done the reinforcing element is subjected to a succeeding driving impact and thereby driven home and across the face of the crotch.

A reinforced clothespin of the character described forms the subject of my pending application Serial No. 432,198, filed February 25, 1942.

A constructional form of machine according to my invention is illustrated in the annexed draw- 55

ings, and is hereinafter described in detail, the scope of the invention being expressed in the appended claims.

In the drawings—

5 Fig. 1 is a plan of a clothespin reinforcing machine embodying the principle of my invention.

Fig. 2 is a front elevation of the machine.

10 Fig. 2a is a view of a portion of a horizontal clothespin guide member and of an inclined feed guide member leading thereto, showing an escape- ment stop for pivotally checking the advance of the leading clothespin and causing the clothespin to gravitate to a vertical position astride of the guide plate while the head of the next adjacent inclined pin abuts the head of the leading pin, the vertical position of the leading pin being indicated by dotted lines.

15 Fig. 3 is a transverse vertical section in a plane through the wire feeding mechanism and the mechanisms for forming succeeding wire reinforcements and for driving a reinforcement into each succeeding clothespin, as on the line 3—3 of Fig. 2.

20 Fig. 4 is a similar section in a plane through the clothespin feeder, as on the line 4—4 of Fig. 1.

25 Fig. 4a is a detail section showing a spring pressure device for temporarily holding the actuating slide of the escapement mechanism included in the clothespin feeder.

30 Fig. 5 is a longitudinal vertical section through a portion of the table adjacent combined wire cutting and reinforcement forming members, showing a reciprocating driver and its apertured guide and also the delivery portion of a clothespin guide plate including a spreader member located in the path of each succeeding reinforcement after the formation of the reinforcing element.

35 Fig. 6 is a transverse vertical section, as on the line 6—6 of Fig. 5.

40 Fig. 7 is a section, similar to Fig. 5, of the combined cutter and former members and adjuncts, showing said members in their raised position, and with the driver element elevated preparatory to driving the reinforcing element.

45 Fig. 8 is a sectional plan of the cutter and former members showing a wire guide block and the apertured driver guide through which the leading end of a strand of wire extends.

Fig. 9 is a perspective view of the wire guide block.

Fig. 10 is a similar view of the combined cutter and former members, showing a part of the actuating devices for said members.

Fig. 11 is a sectional perspective view of the

driver guide, showing the head of the driver as engaged with a reinforcement formed between and supported by the walls of the guide.

Fig. 12 is a sectional elevation showing the delivery end of the guide member for a succession of clothespins, said guide member terminating in a spreader member, and also showing the driver head as supporting a reinforcing element in close relation to the crotch of the clothespin, said driver head being represented as near the limit of its upward stroke with the legs of the reinforcement embracing the spreader, and also as impinging a reinforcing element which has been partially inserted in a preceding clothespin.

Fig. 13 is a sectional elevation as on the line 13—13 of Fig. 12.

Fig. 14 is a similar view showing the driver head at the limit of its inserting stroke and the reinforcing element with its legs spread and partially driven into the head of the clothespin.

Fig. 15 is a sectional elevation as on the line 15—15 of Fig. 12, but showing the driver head at the limit of its upper stroke and the reinforcing element driven home.

As illustrated in the drawings the supporting frame of the machine includes a bed 15 and a table 16; a drive shaft 17 having its bearings in standards 18 on the bed, and a main shaft 19 parallel with the drive shaft and mounted in bearings in standards 20 rising from the bed, the two shafts having fast thereon intermeshing gears 21 and 22, respectively.

Fixed upon and longitudinally of the table is a clothespin guide comprising preferably a relatively thin plate 23 having at its right hand or discharging end, as viewed in Fig. 2, a reduced extension 24 of special construction constituting a continuation of the upper edge of the plate. This extension functions as a spreader for the legs of the reinforcing element during their insertion in the body of the clothespin, as will be hereinafter described.

The plate 23 is adapted to support astride thereof a row of clothespins C, which row is intermittently movable along the plate to position each succeeding leading clothespin upon, and thereafter remove it from the spreader, as will presently appear.

The clothespins, as viewed in Fig. 2, are delivered to the left hand or receiving end of the guide plate 23 by way of a suitably inclined plate member 25 which merges at its lower end with the guide plate. The higher part of the inclined plate 25 preferably terminates in a horizontal extension 26 of substantial length adapted to receive and support in straddling relation a succession of clothespins. The clothespins may be manually mounted on the horizontal extension 26 and at the same time pushed therealong to the inclined plate 25, down and to the foot of which they freely gravitate so that the head of the leading clothespin somewhat overhangs the receiving end of the guide plate 23, while the succeeding clothespins throughout the row remain in lateral contact.

A suitably mounted stop 27 intercepts the head of the leading descending clothespin adjacent the foot of the inclined plate 25, and as a result the clothespin naturally swings to a vertical position, or substantially so, and straddles the receiving end of the guide plate 23. Thereafter the stop 27 is retracted from the path of the vertical clothespin and the latter is engaged by a suitable feeder, including, for example, an oscillating dog 28 (see Fig. 1) which in its forward

stroke pushes the clothespin a definite distance along the guide plate. The feeder dog in its back stroke moves to a position for engagement with the next succeeding leading clothespin delivered to the guide plate 23. There is also provided a secondary stop 29 which, concurrently with the retraction of the stop 27, is moved into the path of the succeeding clothespin at the foot of the inclined plate 25 as the feeder dog approaches the end of its forward stroke, thus preventing premature advancement of the row of pins astride the inclined plate. (See Figs. 1, 2 and 4.)

In the structure illustrated the stops 27 and 29 are constituted by the free ends of the respective limbs 30 and 31 of an escapement, which limbs are suitably spaced on a horizontal rock shaft 32 journaled in a standard 33 on a detachable base plate 34 fitted in a suitable opening in the table 16. By properly actuating the rock shaft 32 the respective pendant stops 27 and 29 are moved in alternation into and from the paths of the adjacent clothespins; that is to say, when one stop is swung inward the other stop is swung outward, and the converse.

In the present instance the rock-shaft 32 has fast thereon a rearwardly extending arm 35 which is connected by means of a link 36 with the upper portion of a vertically reciprocative slide 37 mounted in a guide 38 depending from the base plate 34. Hence when the slide is raised and lowered the rock-shaft and the pendant escapement members thereon are oscillated. A spring-pressed bolt 39, which is slidably mounted in a fixture 40 on the table, bears against the opposing face of the slide so as to exert thereon sufficient frictional pressure to maintain the slide temporarily in its up and down positions respectively, such face preferably having therein spaced sockets 41 with which the opposing end of the bolt is engaged in alternation. The lower portion of the slide 37 has a lateral stud (or roll) 42 which is freely entered in a suitable cam groove formed in the arcuate face of a sector 43 fast on and concurrently movable with a vertical rock-shaft 44. This rock-shaft is journaled in a suitable bearing 45 on the base plate 34 rearwardly of the guide-plate 23 and is extended below the table. The lower portion of the rock-shaft 44 has fast thereon a pinion 46 in mesh with a horizontal rack 47 which, being slidably mounted in a stationary guide 48 on the under side of the base plate, is periodically reciprocated through suitable actuating means in a manner to oscillate the pinion 46 and therewith the vertical rock-shaft 44 and the sector cam 43, as will presently appear. As shown the groove of the sector cam has a concentric portion 49 exceeding somewhat in width the diameter of the roll or stud 42 of the slide 37 and having adjacent its respective ends bevelled cam surfaces 50 and 51, whereof the surface 50 is located at the bottom wall and the surface 51 is located at the upper wall of the groove. When the oscillating sector cam approaches the limit of its forward stroke, (concurrently with the forward stroke of the clothespin feeder dog), the lower cam surface 50 at the rear of the groove impinges the stud 42 and raises it to the upper wall of the groove, thus correspondingly lifting the slide 37 and thereby partially turning the rock-shaft 32 and the escapement members thereon. At this stage the bolt 39 registers with the lower socket 41 of the slide and temporarily holds the slide and the escapement in set position until the sector cam approaches the limit of its back stroke,

whereupon the cam surface 51 lowers the stud, thus lowering the slide and partially turning the rock-shaft and the escapement members to their preceding condition. The parts thus remain until the sector cam nears the limit of its next forward stroke whereupon the cam surface 50 against coacts with the stud 42 of the slide.

As shown the feeder dog 28, which is pivoted to an inwardly extending arm 52 fast on the upper end of the vertical rock-shaft 44, is moved concurrently with the sector cam, and is also resiliently urged toward the adjacent face of the clothespin guide plate 23 by means, for example, of a suitably-disposed spring 53. When the feeder dog 28 and the cam sector 43 are at the limit of their back strokes the dog is located a short distance rearwardly of the vertical clothespin at the receiving end of the guide plate; the first escapement stop 27 is in active position; the second stop 29 is idle, and the head of the then leading slanting clothespin on the inclined plate 25 is supported by the opposing head of the vertical clothespin. (See Fig. 2a.)

In the initial forward movement of the dog 28 the first stop 27 is moved outward and the second stop 29 is moved inward. Continuing its stroke the dog advances the opposing vertical pin a definite distance along the guide plate 23 while the second stop, being inward, maintains the opposing inclined clothespin in place upon the lower portion of the inclined plate 25. As the dog approaches the limit of its forward stroke the relative positions of the stops 27 and 29 are reversed, that is, the first stop is moved inward and the second stop is moved outward. Consequently the head of the first inclined clothespin moves to and bears against the opposing first stop 27, which clothespin immediately assumes a vertical position upon the guide plate while the next succeeding inclined clothespin leans with its head against the head of the vertical clothespin. In its reverse stroke the dog 28 passes to and slightly beyond the opposing vertical clothespin, the backward movement of the latter being prevented by the then opposing stop 29.

In each succeeding forward stroke of the feeder dog 28 the preceding row of clothespins astride of the horizontal guide plate 23 is advanced a distance equal to the maximum diameter of a clothespin so as to position the leading clothespin of the row (when the row is of sufficient length) upon the spreader 24 previously referred to. In each forward stroke of the feeder after the first clothespin has been positioned upon the spreader the proximate clothespin astride of the spreader is pushed therefrom. This spreader, which is preferably a hardened integral portion of the guide plate 23, is substantially triangular in cross-section, its oppositely inclined faces being on the under side of the spreader and diverging in close proximity to the angular corners of the crotch of the clothespin astride of the spreader. (See Figs. 12, 13 and 14.) The flaring surfaces at the open or entrant portion of the resilient prongs of this clothespin snugly grip a laterally tapering member 54 which projects a short distance above the upper surface of the table 16. (See Figs. 5 and 6.) At this stage the head of the clothespin has passed beneath and in close relation to a channeled thrust member 55 conveniently supported by a bracket 56 rising from the table, which member, in conjunction with the tapering projection, maintains the clothespin in upright position.

The tapering projection 54 is preferably formed by the upper portion of a vertically grooved or channeled structure 57, which depends through and below the table and is fixedly supported by a bracket 58 bolted to the underside of the table. This structure affords a stationary guide for a vertically reciprocative relatively thin plunger 59 which is movable in timed relation to the feeder into and from the space between the prongs of the clothespin astride of the spreader 24. The upper or acting end of the plunger exceeds the width of the clothespin and presents a slightly higher or steplike portion 60 which traverses the slot of the clothespin when it (the clothespin) has been pushed from the spreader, as will presently appear. The lower step portion 61 of the plunger has therein an open transverse slot 62 adapted snugly to receive and laterally support a reinforcing element R of substantially U-form, in inverted position with its upstanding extremities projecting slightly above the adjacent plunger portion 61 and in contact with the respective inner side walls of the guide structure 57.

In the upward stroke of the plunger 59 the reinforcing element engaged therewith is driven toward the crotch of the clothespin, the step portion 61 of the plunger as it approaches the limit of its stroke driving the projecting extremities of the reinforcing element against the opposing inclined faces of the spreader 24 with sufficient force to deflect such extremities outwardly in opposite directions to and through the angular corners of the crotch and into the solid body of the clothespin a substantial distance—but not far enough to bind the crotch to the spreader by the connective portion of the reinforcing element. See Fig. 14. In this effective stroke of the plunger the upstanding legs of the reinforcing element are well supported by the walls of the plunger slot 62, the inner walls of the guide structure 57 and the laterally opposing faces of the prongs of the clothespin. Preferably the slotted step portion 61 of the plunger 59 has formed therein a V-groove 63, which intersects the slot 62 and allows the base of the reinforcing element to advance nearer the apex of the spreader. (See Figs. 11 to 14.)

In the next succeeding descent of the plunger 59 the row of clothespins astride of the guide plate 23 is advanced one step by the feeder dog 28, in consequence of which the clothespin with the legs of the reinforcing element partially embedded therein is pushed fully off the free end of the spreader and placed in vertical alignment with the path of the higher or secondary acting portion 66 of the plunger, being there temporarily held by and between the upper thrust member 55 and the lower tapering projection 54. Hence in the next succeeding effective stroke of the plunger the reinforcing element is driven home and against the crotch of the clothespin by the impact of the secondary acting portion of the plunger on the opposing reinforcing element. (See Fig. 15.) Thereafter during each operating cycle the final driving of a reinforcing element is effected coincidentally with the insertion of a reinforcing element in the clothespin astride of the spreader, it being noted, in passing, that the completed clothespin in each succeeding step advance of the row of clothespins on the guide plate 23 is pushed from the machine and delivered to a suitably located discharge chute 64 or other receiver.

Any suitable mechanism for reciprocating the

plunger 59 in timed relation to the feeder dog 28 may be employed. In the present instance the lower end of the plunger is pivotally connected by means of a link 65 with the free end of a lever 66 pivotally mounted on a transverse fulcrum shaft 67 fixed in a standard 68 on the bed 15. The lever has a lateral roll 69 which is operatively fitted in the race of an adjacent face cam 70 fast on the driven main shaft 19, the contour of the race being such that in a partial rotation of such shaft the lever is idle and in the remainder of the rotation of the shaft the lever is oscillated, thus vertically reciprocating the plunger through the described link connection.

As a simple and efficient means to form the reinforcing element R of wire and properly position such element in the path of the plunger preparatory to each effective stroke of the plunger, the following described mechanism is illustrated:

Formed in the spaced side walls of the plunger guide structure 57 are aligning transverse apertures 71 which are located in a horizontal plane directly above the slot 62 of the plunger when the latter is at the limit of its descent. These apertures are adapted to receive the free end of a strand of wire W extending from the rear of the table 16 and at a right angle to the vertical path of the plunger. The wire is advanced step-by-step to and through the apertures 71, each step being equal to the relatively short length of wire for a single reinforcing element. The wire is intermittently drawn from a suitably disposed spool, or other source, (not shown) by means of a feeder comprising, for example, a horizontal slide 72 mounted on the table and pivotally supporting a dog 73 which in the forward stroke of the slide bites the opposing wire and advances it lengthwise a definite length through and beyond a horizontally perforated guide block 74 located adjacent the apertured back wall of the plunger guide structure 57. As shown the table 16 has formed therein a transverse slot 75 having a bottom plate 76 which, being bolted to the underside of the table, serves as a floor for the wire W and also as a support for the guide block 74. A back stop dog 77 pivotally mounted on a bracket 78 supported adjacent the guide block normally rests upon the underlying wire and prevents retrograde movement of the wire when the feeder slide 72 is retracted.

In the present instance the wire feeder slide is jointed to an upstanding arm 79 fast on a rock-shaft 80 which extends longitudinally of and is journaled in hangers 81 bolted to the table. Also fast on the shaft 80 is a depending arm 82 having a lateral roll 83 which is operatively fitted in the race of a barrel cam 84 fast on the driven main shaft 19, the contour of the cam race being such that during a partial rotation of the cam the arm 82 and the shaft 80 are oscillated in a manner to rock the arm 79 and reciprocate the slide 72 toward and from the plunger guide structure, thereby effecting a determined step advance of the leading end of the wire through the apertured walls of the structure, followed by an extended dwell of the lever at the limit of the back stroke of the slide.

It is to be noted that the clothespin and the respective feeder dogs 28 and 73 are actuated to feed the clothespins and the wire simultaneously. To this end the rock-shaft 80 has fast thereon an upstanding arm 85 which is pivotally con-

nected by a link 850 with the hereinbefore mentioned gear rack 47 in mesh with the pinion 46 on the vertical rock-shaft 44 of the clothespin feeder.

At the limit of each step advance of the wire a length thereof requisite for a reinforcing element is severed from the projecting leading end of the wire through the agency of suitable cutting mechanism, which length when produced spans the path of the plunger 59 between and rests in the apertures of the walls of the guide structure 57. The particular cutter mechanism illustrated comprises a blade 86 fast on a rock-shaft 87 having its bearings in a suitably-disposed bracket 88 bolted to the underside of the table 16. The effective cutting portion 89 of the blade is in inclined relation to the path of the wire and is so arranged that when the blade is raised the wire in its step advance passes freely through the apertures 71 of the guide structure 57. See Fig. 8. Thereupon, by actuation of the rock-shaft 87, the blade is forcibly lowered in sliding contact with the correspondingly inclined outer end of a centrally perforated head 90 through which projects the leading end of the strand of wire, which head is shown as detachably fixed to the block 74. Thus the projecting wire end is sheared from the strand, the severed length having pointed ends.

The rock-shaft 87 has also fast thereon an arm 91 which is connected by means of a link 92 with the free end of a lever 93 pivotally mounted on the shaft 67 previously referred to, which lever has a lateral roll 94 operatively fitted in the race of an adjacent face cam 95 fast on the driven shaft 19. The contour of the cam race is such that in each step advance of the wire the lever 93 is actuated to oscillate the rock-shaft 87 and operate the cutter blade 86, following which the blade remains in raised position until the next succeeding step advance of the wire; and so on the wire is intermittently fed during the operation of the machine.

The rock-shaft 87 has also fast thereon in spaced relation to the blade 86 a wire bending member consisting of a former arm 96 of suitable cross-section which extends freely through a vertical slot 97 in the adjacent narrow wall of the plunger guide structure 57, which slot leads to the path of the plunger in the region of the transverse passage of the wire through the structure. During the oscillation of the shaft 87 the arm 96 is periodically swung in a vertical arc into and from the plunger path. In its inner or down stroke, immediately following the severance of the wire, the arm 96 forcibly impinges the severed wire section spanning the path of the plunger, thereby downwardly bending the section to U-form between the inner walls of the guide structure, and perforce producing a reinforcing element whereof the upstanding legs, bearing against the guide walls, are drawn below the plane of the apertures 71. This done, the arm 96 is swung back to its raised position, thus leaving the reinforcing element slidably supported within the guide structure and directly above the mouth of the slot 62 in the upper end of the underlying plunger. Thereupon the plunger is raised by the action of the cam 70, the legs of the opposing reinforcing element thus being initially embraced by the walls of the slot 62, as seen in Fig. 11, and then being carried upwardly through the guide structure and the space between the prongs of the clothespin astride of the spreader, until the legs impinge the inclined faces of the

spreader, as seen in Fig. 13, and are driven thence in diverging paths through the angular corners of the crotch of the clothespin, as hereinbefore described. The upper portions of the inner faces of the walls of the guide structure are preferably provided with vertical grooves 98 which serve to support and guide the upstanding legs of the reinforcing element during its formation by the former arm 96 and during its initial upward movement by the driving plunger.

Assuming that the guide plate 23 on the table 16 is supplied with a row of clothespins whereof the leading pin straddles the spreader 24 under the thrust member 55 and also embraces the upward projection 54 of the plunger guide structure 57, and assuming, also, that the plunger 59 is at rest at the limit of its downward stroke by virtue of the cooperative relation of the dwell portion of the cam 70 on the main shaft to the actuating lever 66 for the plunger, the operation of the machine during each rotation of said shaft is as follows:

In the rest period of the plunger the rock shaft 80 from which the arm 82 depends is actuated by virtue of the cooperative relation of the arm to the active portion of the cam 84, thus effecting through the upstanding arm 79 and the slide 72 the advancement and retraction of the wire feeding dog 73, and perforce projecting the free end of the wire a determined distance through the perforated guide block 74 and the apertured walls of the plunger guide structure. The back stroke of the dog is followed by a prolonged dwell of the arm 72. During this dwell, as well as during the remainder of the dwell of the plunger actuating lever 66, the rock shaft 87 carrying the cutter 88, 89 and the former arm 96 is oscillated through the described crank and link connection between the rock shaft 87 and the actuating lever 93 under the control of the cam 95 on the main shaft; the contour of the cam race being such that following the upward or return motion of said rock shaft 87 the latter remains at rest for a prolonged period. The cutter in its down stroke severs the end portion of the wire between the block and the plunger guide structure, and immediately thereafter the arm 91 strikes the midportion of the severed wire section and bends it to U-form between the inner walls of the plunger guide structure, the legs of the reinforcement thus formed bearing frictionally against the opposing walls. In the succeeding up stroke of the cutter and the former arm the cutter rises above the path of the wire and the arm 96 is retracted from the path of the plunger. In the dwell of the rock shaft 87 the plunger is raised and lowered to its respective limits, remaining in down position during the reciprocation of the wire-feeding dog 73 and the oscillation of the associated cutter and former arm borne by the rock shaft 87.

In the upward stroke of the plunger the lower step portion 61 at the acting end thereof impinges the opposing reinforcing element previously formed and positioned within the guide structure 57, thus forcing the reinforcement upward in a path extending through the space between the prongs of the clothespin straddling the spreader 24. The divergent faces of the spreader as the plunger approaches the limit of its upward stroke, deflect outwardly the upstanding legs of the reinforcement as such legs pass to and are being partially driven into the respective opposing corners of the crotch of the clothespin.

During the oscillation of the rock shaft 80 to 75

effect the feeding of the wire while the plunger is in down position, the row of clothespins extending along the guide plate 23 is advanced one step by means of the feeder dog 28 on the swinging arm 52, which arm is carried by the vertical rock shaft 44 in the vicinity of the receiving end of the guide plate 23, motion being transmitted to the shaft 44 through the gear 46 thereon by the complementary rack 47 which is linked with the arm 85 fast on the rock shaft 80. Hence in each rotation of the main shaft 19 a clothespin is positioned upon the spreader to receive a reinforcement, and the preceding clothespin with a partially entered reinforcement therein is advanced beyond the spreader so as to position the reinforcement in the path of the higher portion 60 at the acting end of the plunger. Following each reciprocation of the feeder dog 28, the escapement members 30 and 31, which are connected with and controlled by the sector cam 43 on the vertical rock shaft 44, are concurrently actuated to move in alternation into and from the paths of the clothespins at the foot of the feed plate 25, thereby permitting the delivery by gravity to the guide plate 23 of the then leading pin on the inclined feed plate, as hereinbefore described.

I claim:

1. The combination of means for supporting a bifurcated clothespin, means for driving a metallic reinforcing element having spaced legs into the crotch and lengthwise of the interior of the body of the clothespin and with the connection for the legs extending transversely of the crotch, said driving means including a plunger and a structure by which said plunger is guided into and longitudinally of the space between the prongs of the clothespin, said guide structure constructed to support the reinforcing element in the path of the plunger and in a plane transversely of the acting end of the plunger, whereby said plunger in its driving stroke forces said reinforcing element from the guide structure into and along the space between the prongs of the clothespin and with the legs of the element in contact with the inner walls of the prongs and in line with the respective corners of the crotch, said supporting means including a stationary spreader for the legs of said element as they enter the crotch, whereby said legs diverge from the corners of the crotch into and through the body of the clothespin to points a greater distance apart than the width of the crotch.

2. The combination of means for supporting a bifurcated clothespin, said means including a stationary spreader adapted to be straddled by the prongs in close relation to the crotch of said clothespin, a driver reciprocative within and lengthwise of the space between said prongs, and means for supporting a metallic reinforcing element having spaced legs in and transversely of the effective path of the acting end of said driver and with the extremities of said reinforcing element directed toward the spreader and in substantial alignment with the inner walls of the prongs and the respective corners of the crotch of the clothespin.

3. The combination of means for supporting a bifurcated clothespin, said means including a spreader adapted to be straddled by the prongs and in close relation to the crotch of said clothespin, a driver reciprocative within and lengthwise of the space between said prongs, and means for supporting in the effective path of the acting end of the driver a metallic reinforcing element having spaced legs, said acting end having a sec-

ondary driving portion, and means for moving said clothespin and its associated reinforcing element from the spreader and into the effective path of said secondary driving portion.

4. The combination of means for driving between the prongs and into the crotch of a bifurcated clothespin a metallic reinforcement having spaced legs, and means for feeding clothespins successively to the effective path of said driving means, said feeding means comprising a guide member for supporting a plurality of clothespins in straddling relation, said guide member terminating in an extension constituting an integral spreader member upon which each succeeding leading clothespin is positioned at its crotch, whereby the legs of the reinforcement are laterally deflected in the effective stroke of the driving means.

5. In a machine for reinforcing a bifurcated clothespin, the combination of means for supporting a metallic reinforcement having spaced legs, means for supporting a clothespin with the mouth or entrant portion of the space between the prongs of the clothespin in longitudinal alignment with the space occupied by said reinforcement and with the inner walls of said prongs in substantial alignment with the respective legs of the reinforcement, said latter means including a stationary spreader member mounted in spaced relation to said reinforcement-supporting means and in position to be straddled by the portions of the prongs adjacent the crotch of the supported clothespin, and means for driving said reinforcement toward said spreader and inserting the legs of the reinforcement in the corners of said crotch, said driving means including a member movable through the space occupied by said reinforcement and the space between the prongs of the supported clothespin, whereby the legs of said reinforcement are supported and guided by the respective prongs.

6. In a machine for reinforcing a bifurcated clothespin, the combination of means for supporting a metallic reinforcement having spaced legs, means for supporting a clothespin with the mouth or entrant portion of the space between the prongs of the clothespin in longitudinal alignment with the space occupied by said reinforcement and with the inner walls of said prongs in substantial alignment with the respective legs of the reinforcement, said latter means including a stationary spreader member mounted in spaced relation to said reinforcement-supporting means and in position to be straddled by the portions of the prongs adjacent the crotch of the supported clothespin, means for driving said reinforcement toward said spreader and inserting the legs of the reinforcement in the corners of said crotch, said driving means including a driver member movable in a path through the space occupied by said reinforcement and the space between the prongs of the supported clothespin, said driver member having in its acting portion a slot to receive and support the reinforcement.

7. In a machine for reinforcing a bifurcated clothespin, the combination of means for supporting a metallic reinforcement having spaced legs, means for supporting a clothespin with the mouth or entrant portion of the space between the prongs of the clothespin in longitudinal alignment with the space occupied by said reinforcement and with the inner walls of said prongs in substantial alignment with the respective legs of the reinforcement, the second-named means including a stationary projection adapted to be

embraced by the walls of said mouth or entrant portion and including also a stationary spreader member mounted in spaced relation to said projection and in position to be straddled by the portions of the prongs adjacent the crotch of the supported clothespin, and means for driving said reinforcement toward said spreader and inserting the legs of the reinforcement in the corners of the crotch, said driving means including a member movable in a path through the space occupied by said reinforcement and the space between the prongs of the supported clothespin.

8. In a machine for reinforcing a bifurcated clothespin, the combination of a structure having spaced parallel walls, means for positioning between said walls a metallic reinforcement having spaced legs in frictional contact with said walls, means for supporting a clothespin with the mouth or entrant portion of the space between the prongs of the clothespin in longitudinal alignment with the space occupied by said reinforcement and with the inner walls of the prongs in substantial alignment with the respective legs of the reinforcement, said latter means including a stationary spreader member mounted in spaced relation to said structure and in position to be straddled by the portions of the prongs adjacent the crotch of the supported clothespin, a plunger in said structure for forcibly driving said reinforcement toward said spreader and inserting the legs of the reinforcement in the corners of the crotch, and mechanism for reciprocating said plunger through the space occupied by the reinforcement within the structure and the space between the prongs of the supported clothespin.

9. In a machine for reinforcing a bifurcated clothespin, the combination of a structure having spaced parallel walls, means for positioning between said walls a metallic reinforcement having spaced legs in frictional contact with said walls, means including the exit portion of the structure for supporting a clothespin with the mouth or entrant portion of the space between the prongs of the clothespin in longitudinal alignment with the space occupied by said reinforcement and with the inner walls of the prongs in substantial alignment with the respective legs of the reinforcement, said latter means also including a stationary spreader member mounted in spaced relation to said structure and in position to be straddled by the portions of the prongs adjacent the crotch of the supported clothespin, a plunger in said structure for forcibly driving said reinforcement toward said spreader and inserting the legs of the reinforcement in the corners of the crotch, and mechanism for reciprocating said plunger through the space occupied by the reinforcement within the structure and the space between the prongs of the supported clothespin.

10. In a machine for reinforcing a bifurcated clothespin, the combination of a structure having spaced parallel walls provided with aligning transverse apertures to receive and support the respective ends of a measured length of wire transversely spanning the space between said walls, severing means for the wire, means for bending said wire length in the space between said walls to form a reinforcement having spaced legs in frictional contact with the opposing walls, means for supporting a clothespin with the mouth or entrant portion of the space between the prongs of the clothespin in longitudinal alignment with the space occupied by said reinforcement and with the inner walls of the prongs in substantial alignment with the respective legs of the reinforcement.

reinforcement, said clothespin supporting means including a stationary spreader member mounted in spaced relation to said structure and in position to be straddled by the portions of the prongs adjacent the crotch of the supported clothespin, a plunger in said structure for forcibly driving said reinforcement toward said spreader and inserting the legs of the reinforcement in the corners of the crotch, and mechanism for reciprocating said plunger through the space occupied by the reinforcement within the structure and the space between the prongs of the supported clothespin.

11. In a machine for reinforcing bifurcated clothespins, the combination of means for feeding a strand of wire step-by-step, said means including a rock shaft, a lever fast thereon, and means for actuating said lever, means for cutting the leading end of said wire into succeeding definite lengths and for bending each length to produce a reinforcement element having spaced legs, means for feeding clothespins step-by-step to position each succeeding leading clothespin with its mouth or entrant portion in alignment with a reinforcement element, said clothespin feeding means including an actuating member fast on said rock shaft, a reciprocating plunger for driving each succeeding reinforcement between the prongs and toward the crotch of the adjacent clothespin, and means for reciprocating said plunger in timed relation to said wire-feeding means and clothespin-feeding means.

12. In a machine for reinforcing a bifurcated clothespin, the combination of a structure having spaced parallel walls provided with aligning transverse apertures to receive and support the respective ends of a measured length of wire spanning the space between the walls, wire severing means including a cutter movable across the path of the wire adjacent one of said apertures, a rock shaft for said cutter mounted exteriorly of said structure, and means for actuating said shaft, means for bending said wire length in the space between the walls of said structure to form a reinforcement having spaced legs in frictional contact with the walls, said bending means comprising a forming member fast on said rock shaft and movable across and from the path of the wire between the inner walls of the structure, means for supporting a clothespin with the mouth or entrant portion of the space between the prongs of the clothespin in longitudinal alignment with the space occupied by said reinforcement within the structure, a plunger in said structure for forcibly driving said reinforcement toward and inserting its legs in the corners of the crotch of the clothespin, and means for reciprocating said plunger through the space occupied by the reinforcement within the structure and the space between the prongs of the supported clothespin.

13. The combination of means for applying a reinforcement to a bifurcated clothespin, and means for feeding clothespins to said applying means, said feeding means comprising an inclined feed member to support in straddling relation a row of clothespins and allow the row to descend intermittently to the lower part of said member, a substantially horizontal guide member extending longitudinally from the foot of said feed member to receive in straddling relation each succeeding leading clothespin, and means for causing the leading clothespin on said feed member to assume a vertical position as it passes therefrom to said guide member, the last mentioned means comprising oppositely-movable

stops respectively mounted adjacent the upper paths of the leading clothespin and the next succeeding clothespin of the row on the inclined feed member, means for concurrently actuating said stops at determined intervals to move them into and out of the respective paths of the adjacent clothespins in alternation, and means for advancing each vertically-disposed clothespin a determined distance along said guide member when the stop adjacent such vertical clothespin is outward and the stop adjacent the next succeeding inclined clothespin is inward.

14. The combination of means for applying a reinforcement to a bifurcated clothespin, and means for feeding clothespins to said applying means, said feeding means comprising an inclined feed member to support in straddling relation a row of clothespins and allow the row to descend intermittently to the lower part of said member, a substantially horizontal guide member extending longitudinally from the foot of said feed member to receive in straddling relation each succeeding leading clothespin, and means for causing the leading clothespin on said feed member to assume a vertical position as it passes therefrom to said guide member, the last mentioned means comprising oppositely-movable stops respectively mounted adjacent the upper paths of the leading clothespin and the next succeeding clothespin of the row on the inclined feed member, means for concurrently actuating said stops at determined intervals to move them into and out of the respective paths of the adjacent clothespins in alternation, said actuating means including an oscillatory member, and connections between said oscillatory member and the stops, and means for advancing each vertically-disposed clothespin a determined distance along said guide member when the stop adjacent such vertical clothespin is outward and the stop adjacent the next succeeding inclined clothespin is inward.

15. The combination of means for applying a reinforcement to a bifurcated clothespin, and means for feeding clothespins to said applying means, said feeding means comprising an inclined feed member to support in straddling relation a row of clothespins and allow the row to descend intermittently to the lower part of said member, a substantially horizontal guide member extending longitudinally from the foot of said feed member to receive in straddling relation each succeeding leading clothespin, and means for causing the leading clothespin on said feed member to assume a vertical position as it passes therefrom to said guide member, the last mentioned means comprising oppositely-movable stops respectively mounted adjacent the upper paths of the leading clothespin and the next succeeding clothespin of the row on the inclined feed member, means for concurrently actuating said stops at determined intervals to move them into and out of the respective paths of the adjacent clothespins in alternation, said actuating means including an oscillatory member, and connections between said oscillatory member and the stops, and means for advancing each vertically-disposed clothespin a determined distance along said guide member when the stop adjacent such vertical clothespin is outward and the stop adjacent the next succeeding inclined clothespin is inward, said advancing means including a feed dog and operative connection between said dog and the oscillatory member.

16. The combination of means for inserting a

metallic reinforcement in a bifurcated clothespin, and means for feeding clothespins to said inserting means, said feeding means comprising an inclined feed member to support in straddling relation a row of clothespins and allow the row to descend intermittently to the lower part of said member, a substantially horizontal guide member extending longitudinally from the foot of said feed member to receive in straddling relation each succeeding leading clothespin, and means for causing the leading clothespin on said feed member to assume a vertical position as it passes therefrom to said guide member, the last mentioned means comprising oppositely-movable stops respectively mounted adjacent the upper paths of the leading clothespin and the next succeeding clothespin of the row on the inclined feed

member, means for concurrently actuating said stops at determined intervals to move them into and out of the respective paths of the adjacent clothespins in alternation, said actuating means including an oscillatory shaft, means for actuating said shaft, a cam element fast on said shaft and connections between said cam element and the stops, and means for advancing each vertically-disposed clothespin a determined distance along said guide member when the stop adjacent such vertical clothespin is outward and the stop adjacent the next succeeding inclined clothespin is inward, said advancing means including a feed dog and a pivotal connection between said dog and said oscillatory shaft.
